UNITED STATES PATENT OFFICE

2,611,838

HIGH VOLTAGE CIRCUIT BREAKER

Elmer Goessel, Philadelphia, Pa., assignor to
I-T-E Circuit Breaker Company, Philadelphia,
Pa., a corporation of Pennsylvania

Application June 27, 1947, Serial No. 757,356

5 Claims. (Cl. 200—50)

1

My present invention relates to high voltage, high capacity circuit breakers and more particularly to truck mounted circuit breakers having a racked in position, a test position and a racked out position.

Among the objects of the present invention is the provision for a novel truck mounted circuit breaker racking mechanism having provisions for moving the circuit breaker to a test position without moving the circuit breaker racking truck.

Another important object of the present invention is the provision of a racking mechanism which precludes racking out until the circuit breaker is in the disconnect or test position.

Still another important object of the present invention is the provision of a removable circuit breaker which is easily moved to a test position.

Still another object of the present invention is the provision of a novel switchgear assembly having a movable circuit breaker which has a connect and a disconnect position within the housing of the switchgear, and where the movement of the circuit breaker from one position to the other is accomplished by a rack screw mechanism which moves the circuit breaker with respect to a releasably engaged arm.

The foregoing and many other objects of my invention will become apparent from the following description of the drawings in which:

Figure 1 is a side view in perspective, partly broken away showing my novel circuit breaker assembled and mounted on a truck.

Figure 2 is a side view of the racking and indicator assembly.

Figure 3 is a top view of the racking and indicator assembly.

Figure 4 is a front view of the racking and indicator assembly.

Figures 5 and 6 are schematic views illustrating successive steps in assembling my novel circuit breaker.

Referring now to Figure 1, my novel circuit breaker, comprising a fixed contact 167 and a movable contact 206 mounted on movable arm 52, operated to open position by fault current responsive mechanism 46 and operated to closed position by closing mechanism 49 (more fully described in the co-pending application Serial No. 721,648, filed January 11, 1947), is shown preferably mounted on a movable truck. The movable truck comprises a back main supporting structure which includes the vertical support members 10 and 11 connected together and interbraced at the lower end by the Masonite panel 12 and at the central and upper portion by the

cross-bars 13, 14 and 15 which are connected as shown in Figures 5 and 6, in any appropriate manner, as for instance by bolts and nuts to the vertical members 10 and 11. The lower ends of the vertical members 10 and 11 are provided with bearings 18 for the shaft 19 which carries the rear wheels 21 of the truck. The vertical members 10 and 11 together with the cross bracing elements above described and the wheels 21 constitute a single unitary member of assembly.

Certain of the assemblies are standard and require no specific discussion here. Thus, the control panel assembly 41 and the trip unit assembly 48 may be substantially standard units which require no specific description. Also, the control switch contacts indicated generally at 10 of Figure 1 and the grounding contacts 71, 72 of Figure 1 may be standard units. The essential elements as above pointed out with respect to these units is the unit assembly arrangement which is possible with the construction herein shown.

The rear end of the operating mechanism assembly 46 is supported on the cross bar 14 which is held by the bolts 75, 75 across the top of the lower panel 12. Crossbar 14 also provides means for supporting additional assemblies.

The operation mechanism utilizes as closely as possible the simple principle of the lever operated switch with only enough addition thereto to provide automatic response to over-current conditions in order to trip the circuit breaker and also to provide a solenoid closing means. The simplification of this operating mechanism makes possible the production of the inexpensive circuit breaker herein described.

Thus, while the arc chute assembly and the blow-out assembly make possible the high capacity operation and high speed operation which are essential to the operation of the circuit breaker as a whole, the simplicity of the other assemblies makes possible the economical and efficient construction.

The individual unit assemblies facilitate storage of parts preparatory to final assembly and thus makes it possible to fill orders quickly.

Thus the first subassembly which consists of the back panel and the back wheels 21 is essentially a simple flat member which may readily be stored and does not take up any substantial amount of space (see Figure 1).

Heretofore, the difficulty encountered in pre-manufacture of subassemblies in anticipation of future orders resided in the fact that the main frame of the circuit breaker or other switchgear

usually was as big as the circuit breaker itself, so that the manufacture and especially the storage of the main frame presented the same problem as the storing of an entire circuit breaker. No real economy was effected by premanufacture of the main frame since the entire circuit breaker could be stored just as readily.

By means of my novel device, the back panel and the rear wheels of the truck which constitute a single flat structure may readily be stored awaiting specific orders for assembly of specific circuit breakers.

The truck structure is completed by means of a lower or bottom platform 23, which carries a front wheel 24 in the front swivel 25 (Figure 1). The bottom platform 23 is secured at the rear end to the lower end of the vertical members 10 and 11 above the bearings 17 and 18 for the rear wheel. The bottom platform 23 in connection with the back panel, the vertical supporting members 10 and 11 and their interbracing structure taken together with the rear wheels 21 and the front swivel wheel 24 comprise the truck or mounting for the circuit breaker. Thus the bottom platform 23 and the front swivel wheel 24 constitute a single subassembly which may readily be stored without requiring any additional space and which may readily be attached by two screws to the lower end of the vertical members 10 and 11.

This type of unitary subassembly construction which may readily be interconnected with other elements in order to make a complete truck, facilitates modification and variation of subassemblies in order to meet the specific orders.

Thus in the event various control elements must be multiplied to a substantial extent in the final circuit breaker thus requiring perhaps a custom built lower platform 23, this lower platform 23 may be built to the unique specifications of the customer and may then be combined with the standard back panel construction which is kept in stock. However, the entire truck construction including the first and second subassemblies above described are built in full anticipation of all requirements to which the particular circuit breaker may be put, so that particular custom made back or bottom portions of a truck will be required only in exception cases.

Each of the upper and lower terminal assembly members 30 and 31 also carry the spring biased disconnect contact elements 38, 38 also herein-after more specifically described in connection with Figure 1, but shown also in Patent Number 2,029,028. The intermediate cross bar 13, which is secured to the vertical members 10, 11 and 32 by the bolts 40, also carries at its outer end the wheels 42 on an appropriate shaft extension thereof, the said wheels 42 cooperating with appropriate tracks in the compartment to guide the truck into and out of the compartment properly.

The racking and indicator assembly shown generally at 43 of Figure 1 also carries the front wheels 44, 44 to ride on the guide tracks of the compartment in which the circuit breaker is housed.

The racking and indicator assembly 43 which is more specifically described in the parent application Serial No. 721,648, filed January 11, 1947, is supported from the mechanism assembly. The control panel assembly 47 is supported by the lower platform 23 of the circuit breaker as is also the trip unit assembly 48. The solenoid

closing mechanism 49 is a part of the operating mechanism assembly 46.

The movable contact assembly shown generally at 50 of Figure 1 is connected at its lower end to the lower terminal assembly 31 in the manner hereinafter described, and is provided with a link 51 which is connected to the contact operating arms 52 projecting up from the operating mechanism assembly 46. The movable contact bridge assembly which of course has as many poles as there are upper and lower terminal assemblies, three in the particular instance shown, is provided with contact elements.

In Figures 2, 3 and 4, I have shown, the racking and indicator assembly, the position of which is shown further in Figure 1 and which is carried by the operating mechanism assembly 46. The arm 400 carries at its outer ends the rollers 44, 44 which roll upon the track of the cubicle or compartment. Latches 500 in the cubicle 501 hold the arm 400 and lock it in position (see Figures 2 and 3).

As shown in Figures 2 and 3 the latches 500 have pivoting shafts 502 which are supported by the cubicle walls 501. The latches 500 each have a supporting bar 503 and a latching bar 504. The supporting bars 503 are pivoted on the shafts 502 described above and are perpendicular to the latching bars 504. Each of the latching bars 504 have a handle 505 which is used to move the latches 500 into and out of latching position.

The arm 400 is part of the racking truck structure as described above so that when the circuit breaker is racked in, the truck and thus the arm 400 therewith is restrained from further entry. The latches 500 in latching position prevent movement of the arm 400 in the opposite direction so that when latched, the arm 400 cannot be moved. The movements of the truck are facilitated as described above by the movement of the rollers 42 and 44 on the track 507.

When the racking crank is inserted through opening 402 in the front plate 403 into the socket 404 of the racking screw 405 and turned, the relative positions of the frame 406 comprising the side elements 407, 407 and the arm 400 are changed. Since the frame 406 is fastened to the front wall of the mechanism 46 and the arm 400 is held in a fixed position within the cubicle 501 by latches 500, the rotation of screw 405 moves the breaker from test to operating position.

This is so because the screw 405 passes through a threaded opening 410 in arm 400 and is rotatably carried in the bearing 411 of the rear frame element 412 of the frame 406. A shutter 420 prevents the insertion of the crank through opening 402 into the racking screw 405 whenever the breaker is closed. The indicator 430 is operated by link 421 which is connected at one end to the bell crank arm 431 of the indicator 430, and at the other end to the pin 109 in the contact operating arms 52. When the breaker is closed by either the solenoid closing mechanism 49 or the manual closing arm 130, the contact operating arms 52 are rotated counter-clockwise (with respect to Figure 1) and thereby draws the link 421 back to actuate the counter 441 and the indicator 430. When the indicator 430 is moved to the right with respect to Figures 2 and 3 the breaker is in the closed position and the indicator 430 registers "On." At the same time the centering spring 422 draws the shutter 420 to the right covering the opening 402. This prevents the racking crank from be-

ing inserted and the breaker from being racked out while in the closed position when it might be in service or conversely from being racked in, while closed, thereby damaging the separable contacts 38—38.

Since many variations and modifications of my invention should now be obvious to those skilled in the art, I prefer to be bound not by the specific disclosure herein contained, but only by the appended claims.

I claim:

1. In an electrical switchgear assembly, a stationary housing, a removable circuit breaker having a connected position within said housing in which said circuit breaker is connected to an electrical circuit and a disconnected position within said housing in which said circuit breaker is disconnected from the electrical circuit; opposite side walls and a rear wall for said housing, an arm extending between said side walls, members at said side walls for releasably engaging and positioning the ends of said arm, said arm including a threaded opening intermediate its ends, a racking screw mechanism connected to and movable with said circuit breaker, the threads of the screw meshing with the threads in the opening for permitting rotation and transverse movement of said screw with respect to said arm while said arm is held from movement by said members, said circuit breaker moving with said screw transversely with respect to said arm from connected position at said rear wall of said housing to disconnected position, and movement from disconnected position toward said rear wall to connected position.

2. In an electrical switchgear assembly, a stationary housing, a removable circuit breaker having a connected position within said housing in which said circuit breaker is connected to an electrical circuit and a disconnected position within said housing in which said circuit breaker is disconnected from the electrical circuit; opposite side walls and a rear wall for said housing, an arm extending between said side walls, members at said side walls for releasably engaging and positioning the ends of said arm, said arm including a threaded opening intermediate its ends, a racking screw mechanism connected to and movable with said circuit breaker, the threads of the screw meshing with the threads in the opening for permitting rotation and transverse movement of said screw with respect to said arm while said arm is held from movement by said members, said circuit breaker moving with said screw transversely with respect to said arm from connected position at said rear wall of said housing to disconnected position, and movement from disconnected position toward said rear wall to connected position, said racking screw having a socket, a crank adapted to be screwed in said socket for rotating said racking screw to operate said arm into connected and disconnected position.

3. In an electrical switchgear assembly, a stationary housing, a removable circuit breaker having a connected position within said housing in which said circuit breaker is connected to an electrical circuit and a disconnected position within said housing in which said circuit breaker is disconnected from the electrical circuit; opposite side walls and a rear wall for said housing, an arm extending between said side walls, members at said side walls for releasably engaging and positioning the ends of said arm, said arm including a threaded opening intermediate its

ends, a racking screw mechanism connected to and movable with said circuit breaker, the threads of the screw meshing with the threads in the opening for permitting rotation and transverse movement of said screw with respect to said arm while said arm is held from movement by said members, said circuit breaker moving with said screw transversely with respect to said arm from connected position at said rear wall of said housing to disconnected position, and movement from disconnected position toward said rear wall to connected position, said circuit breaker having cooperable contacts having engaged and disengaged positions and a shutter mechanically connected to and directly operated by said cooperable contacts for preventing insertion of said crank in said socket when said cooperable contacts are in engagement.

4. In an electrical switchgear assembly, a stationary housing, a removable circuit breaker having a connected position within said housing in which said circuit breaker is connected to an electrical circuit and a disconnected position within said housing in which said circuit breaker is disconnected from the electrical circuit, opposite side walls and a rear wall for said housing, an arm extending between said side walls, members at said side walls for releasably engaging and positioning the ends of said arm, said arm including a threaded opening intermediate its ends, a racking screw mechanism connected to and movable with said circuit breaker, the threads of the screw meshing with the threads in the opening for permitting rotation and transverse movement of said screw with respect to said arm while said arm is held from movement by said members, said circuit breaker moving with said screw transversely with respect to said arm from connected position at said rear wall of said housing to disconnected position, and movement from disconnected position toward said rear wall to connected position, said circuit breaker having cooperable contacts having engaged and disengaged positions, and an indicator mechanically connected to and directly operated by said cooperable contacts for indicating the closed and open conditions of said contacts.

5. In an electrical switchgear assembly, a stationary housing, a removable circuit breaker having a connected position within said housing in which said circuit breaker is connected to an electrical circuit and a disconnected position within said housing in which said circuit breaker is disconnected from the electrical circuit, opposite side walls and a rear wall for said housing, an arm extending between said side walls, members at said side walls for releasably engaging and positioning the ends of said arm, said arm including a threaded opening intermediate its ends, a racking screw mechanism connected to and movable with said circuit breaker, the threads of the screw meshing with the threads in the opening for permitting rotation and transverse movement of said screw with respect to said arm while said arm is held from movement by said members, said circuit breaker moving with said screw transversely with respect to said arm from connected position at said rear wall of said housing to disconnected position, and movement from disconnected position toward said rear wall to connected position, said circuit breaker having cooperable contacts having engaged and disengaged positions, a shutter directly operated by said cooperable contacts for preventing insertion of said crank in said socket when said cooperable contacts are in engagement.

tacts are in engagement, and an indicator connected to said cooperable contacts for indicating the closed and open conditions of said contacts.
